CLAIM

The ornamental design for a valve handwheel cap, as shown and described.

DESCRIPTION

Figure 1.1 is an isometric view of a valve handwheel cap according to a first embodiment of the design;

Figure 1.2 is a top view of the valve handwheel cap shown in Figure 1.1;

Figure 1.3 is a bottom view of the valve handwheel cap shown in Figure 1.1;

Figure 1.4 is a side view of the valve handwheel cap shown in Figure 1.1;

Figure 2.1 is an isometric view of a valve handwheel cap according to a second embodiment of the design.

Figure 2.2 is a top view of the valve handwheel cap shown in Figure 2.1;

Figure 2.3 is a bottom view of the valve handwheel cap shown in Figure 2.1;

Figure 2.4 is a side view of the valve handwheel cap shown in Figure 2.1.

(Continued)

Any broken lines are for illustrative purposes only and form no part of the claimed design.
